LABORATORY CONTROL VALVE

Charles du B. Arcularius, New Canaan, Conn., assignor to Laboratory Furniture Co., Inc., Long Island City, N. Y., a corporation of New York

Application September 22, 1949, Serial No. 5,126

Term of patent 14 years

(Cl. D91—3)

To all whom it may concern:

Be it known that I, Charles du B. Arcularius, a citizen of the United States and a resident of New Canaan, county of Fairfield, and State of Connecticut, have invented a new, original, and ornamental Design for a Laboratory Control Valve, of which the following is a specification, reference being had to the accompanying drawing, forming a part hereof, in which

Figure 1 is a top plan view of a laboratory control valve embodying my new design;

Figure 2 is a view in front elevation of the laboratory control valve shown in Figure 1; and

Figure 3 is a view in end elevation of the laboratory control valve as viewed from the right of Figure 2, the hose connection illustrated in dotted lines in Figures 1 and 2 having been omitted for convenience of illustration.

The essential features of my design reside in the portions shown in full lines.

I claim:

The ornamental design for a laboratory control valve, as shown and described.

CHARLES DU B. ARCULARIUS.
